UNITED STATES PATENT OFFICE

PERCIVAL ARTHUR BENTLEY, CHARLES FREDERICK MANGER, AND CARLYLE HERBERT WAINWRIGHT, OF LEICESTER, ENGLAND, ASSIGNEES TO THE BENTLEY ENGINEERING COMPANY, OF LEICESTER, ENGLAND

KNITTING MACHINE

Application filed July 30, 1929, Serial No. 382,137, and in Great Britain August 2, 1928.

This invention concerns improvements in knitting machines.

In the formation of a welt—in the case of, say, a sock—in a rib-knitting machine, loops 5 of the yarn are held by needles of the rib bed while needles of the plain bed knit a sufficient number of courses to form the welt, the loops above mentioned being then knitted into the fabric in the ordinary way.

10 The loops thus knitted into the work, present thereon an appearance which differs, somewhat conspicuously, from the remainder of the knitting, but this difference is usually of little importance considering that 15 the loops in question occur on the inner side of the work and thus are hidden during wear, even in the case of a sock.

In cases, however, where it is desired that 20 the top of the sock, in wear, be turned outwardly and folded down, the normal method of knitting the welt is objectionable in that the loops above referred to are brought into view thus detracting from the appearance of the article.

25 An object of the present invention is to provide a method of knitting whereby this objection is overcome.

A feature of the invention is a method of 30 forming a welt in a rib-knitting machine which method is characterized by the fact that the courses forming the welt are knitted by needles of the rib bed of the machine.

35 By this method, the loops above referred to are formed on the outer side of the article and are hidden from view when the top of the sock or the like is turned outwardly and folded down.

40 Another feature of the invention is a rib-knitting machine for forming a welt according to a method of the present invention comprising web holders or equivalent devices co-operating with needles of the rib bed in the knitting of the welt.

45 Such a machine may, in accordance with a further feature of the invention, be one wherein needles of the plain bed are under control of a cam track that maintains them in a position where loops of yarn are not 50 knitted but are retained by said needles of

the plain bed during the formation of the welt.

Other features of the invention will be obvious to those skilled in the art from a consideration of the description hereinafter set forth of a convenient construction according to the invention, reference being made to the accompanying diagrammatic drawings in which:—

55 Figure 1 is a side elevation partly in section of the upper portion of a knitting machine illustrative of a construction according to this invention;

60 Figure 2 shows a portion of the machine of Figure 1 with the parts in a different position;

65 Figure 3 is a plan of a cam plate that is employed to operate a set of web holders which are provided in the upper needle cylinder;

70 Figure 4 is a plan of adjusting means for the cam plate shown in Figure 3;

75 Figure 5 is a development of the cam box for the lower needle cylinder and shows in addition to the usual cams, other cams which are provided in accordance with the present invention;

80 Figure 6 is a detail of a switch cam hereinafter referred to;

85 Figure 7 illustrates the manner in which the latches of the rib needles are maintained open during a portion of the knitting operation; and

Figure 8 is a diagrammatic view illustrating the manner in which the needle latches are deflected in order to clear the yarn traps during one phase of operation of the machine.

The invention is applicable to knitting machines capable of performing plain and rib knitting by two sets of needles whether the needles are carried in superposed cylinders or in beds of other type but the invention will be described by way of example in connection with the type of superposed cylinder machine which is exemplified in the specification of British Letters Patent Nos. 15,008/1900; 24,290/1912; and 171,483.

90 A convenient construction of mechanism and a method of knitting performed there-

by, both illustrative of features of the invention, will now be described as applied to and employed in, respectively, a machine substantially like the machine described in 5 the specification of British Letters Patent No. 301,350, except as modified as hereinafter indicated.

In the present construction, the upper needle cylinder 10 which contains the rib 10 needles is provided with a set of web holders 12 (Figures 1 and 2) carried in tricks in a plate or block 14 which is located near the bottom edge of the cylinder and rotates with the cylinder. The tricks in this plate 14 15 extend radially of the plate and below the plate there is a cam plate 16 (see also Figure 3) having on its upper face a cam groove 18 which engages butts 20 formed on the web holders 12 and thereby moves 20 the web holders outwardly between the rib needles to cooperate therewith at the appropriate times. The cam plate 16 is normally stationary but can be moved up and down and adjusted angularly as hereinafter explained. The cam plate 16 is secured to a 25 rod 22 which extends axially of the cylinder and is pressed upwardly by a spring 24 into engagement with a screw 26 in one end of a lever 28 pivoted at 30 between ears on 30 a member 32 that is mounted for vertical adjustment upon the machine frame. The other end of the lever 28 is engaged by the upper end of a rod 34 the lower end of which is in the path of a cam 36 on a control 35 drum 38. The action of the cam 36 and spring 24 causes the cam plate 16 and the web holder plate 14 to be lowered and raised at such times in the knitting operation as the web holders 12 as a whole are to be 40 brought into and taken out of action respectively, it being observed that in their upper position the web holders are disposed at a level above that at which the yarn is fed to the needles, the web holders being thus 45 out of engagement with the yarn. By thus raising the web holders in the cam 16, ample clearance is afforded in the gap between the two needle cylinders when heel and toe pouches are being knitted. To adjust the 50 timing of the web holders 12 in their radial movement, the cam plate 16 can be adjusted angularly about the axis of the rod 22, the adjusting means shown herein comprising two opposed set screws 40 mounted (see 55 Figure 4) in lugs 42 on the machine frame and abutting against the depending end of an arm 44 secured to the rod 22. The hub of this arm 44 serves as an abutment for the pressure exerted by the spring 24, which 60 spring in the construction shown surrounds a boss 46 on the machine frame and presses against a cap or washer 48 bearing against the said hub.

Each web holder 12 is in the form of a 65 thin blade which is so shaped (as best shown

in Figure 2) as to comprise two horizontal portions 121, 122 arranged at different levels, the inner horizontal portion 121 of the blade has formed upon its lower side the butt 20 that enters the cam groove 18 70 while at the front end of the outer horizontal portion 122 there is a downwardly projecting lip 123. At the location where knitting is performed by the needles there is secured to the under-side of the cam plate 75 16 a thin and somewhat narrow blade 50 (see also Figure 3) arranged radially of the cam plate with its outer end (as shown in Figure 1) in close proximity to the inner side of the downwardly-projecting lip 123 80 of the web holder when the web holder is in its innermost position in its trick. The function of this blade is to prevent the yarn, while being pulled up by the rib needles, from passing from off the bottom of the portion 122 of the web holder upwardly on to the portion 121 thereof and thus to ensure that the formed loop is held down so that the needle can draw the next loop through it. 85

In the present machine, the needles of the upper or rib cylinder knit the courses that 90 make up a welt, the needles of the bottom cylinder at that time merely holding the loops. During the formation of the welt courses the bottom needles are thus not required to have imparted to them any knitting movements and to this end there is provided in the cam box surrounding the bottom cylinder an idle cam track (indicated 95 by a chain line in Figure 5) along which 100 run, at the time in question, the butts of the needle sliders. To permit these butts to move into the idle track as hereinafter explained, a bolt cam 52 (Figures 2 and 5) is provided which is operated by a forked wedge 54 which straddles the stem 56 of the bolt cam and acts upon a T-shaped end 58 of said stem. The forked wedge is moved at the appropriate time by connections from the control drum 38, these connections comprising, in the construction illustrated, a cam 60 (Figure 1) on the control drum arranged to engage the lower end of a rod 62, the upper end of which bears against one end of a lever 64 pivoted at 66 between ears on a member 68 that is mounted for vertical adjustment on the machine frame. The other end of the lever 64 has threaded in it a screw 68 engaging a rod 70 upon the lower end of which the wedge 54 is secured. 110 115 120

It has been found convenient to employ as part of the idle track aforesaid a portion 72 of a cam track that is used during reciprocating knitting in the formation of the heel and toe pouches. To utilize such portion and yet to enable it to perform its original function during the reverse stroke of the reciprocating movements of the needle cylinder, the entrance into such portion from the idle track is by way of a spring-con- 125 130

trolled switch cam 74 which can be moved by the slider butts into the position indicated in chain-lines in Figure 5 to permit the slider butts to pass into such portion during 5 the rotary movement of the cylinders while the welt is being formed but yet springs back to the position indicated in full lines in Figure 5 to cause the butts to run in the appropriate track while reciprocatory knitting 10 is being performed. This spring-controlled cam 74 has its stem 76 (Figure 6) mounted in a bearing plate 78 secured to the cam box, a spring 80 secured at one end to the plate 78 and at the other to a transverse pin 82 in the stem 76 tending to move the cam 74 into its full-line position in Figure 5.

During welt-formation, the needles of the bottom cylinder are merely holding a loop 20 and as a consequence their latches are not under control and if they happen to swing out at right angles to the needle shank or thereabouts are liable to strike the yarn-trappers that are employed in this machine. 25 To avoid this possibility the idle track in the neighbourhood of the trappers (i.e. the part of the track indicated at 84) is shaped so as slightly to raise the needles to a position where the latches cannot foul the trappers.

30 The manner in which the needle latches are moved to clear the trappers is indicated diagrammatically in Figure 8 of the drawings by the line X, the trappers being indicated at Z and the shaded portions of these 35 trappers which the latches must clear being shown at Y.

In order to remove from action those needles that are not required during reciprocatory knitting, the needle sliders are provided 40 with long butts. In the present machine, in the bringing of all the butts into the idle track, these long butts are utilized to prevent possible breakage by reason of a butt striking a corner of the track as the butt 45 enters the track. For this purpose the bolt cam 52 has two operative positions, namely one in which it will engage only the long butts which extend round half of the needle circle, and a second position where it engages 50 the short butts which extend round the other half of said circle. The first of these positions is shown in Figure 2 where the wedge 54 has been moved downwardly by the action of a step 86 (Figure 1) on the 55 cam 60 to an extent sufficient to withdraw the bolt cam 52 from the path of the short butts. Figure 1 shows the position of the machine parts when the bolt cam 52 is in the second of these two positions. In arriving 60 at this second position, the bolt cam has been moved by an appropriate spring (not shown) inwardly toward the needle cylinder as far as is permitted by the wedge 54. The bolt cam 52 is so timed as to move 65 into the first position during the passing of

the long butts which it still continues to operate, but the short butts, when they arrive at the location of the bolt cam 52, will not be operated by that cam but will pass into the idle track. The bolt cam 52 is then 70 completely withdrawn by the high part of the cam 60 before the long butts arrive again at the bolt-cam location so that the long butts also will now pass into the idle track. 75

We claim:—

1. In a rib-knitting machine of the cylinder type having upper and lower needle beds, the combination with a bank of web-holders adapted to cooperate with the needles of one of said beds to form a welt, of means driven from the machine for shifting said bank of web-holders axially of the cylinders to provide clearance between the upper and lower needle beds in the knitting 85 of heel and toe pouches.

2. In a rib-knitting machine of the cylinder type having upper and lower needle beds, the combination with a bank of web-holders adapted to cooperate with the needles of one of said beds to form a welt, of a cam for actuating said web-holders, and means driven from the machine for shifting said cam and web-holders axially of the 90 cylinders to provide clearance between the upper and lower needle beds in the knitting 95 of heel and toe pouches.

3. In a rib-knitting machine of the cylinder type having upper and lower needle beds, the combination with a bank of web-holders adapted to cooperate with the needles of one of said beds to form a welt, of a cam track for actuating the needles in the other of said beds during the rib-knitting operation, an idle cam track for controlling the position of the needles in the last named bed during the formation of a welt, means for associating the needles in the last named bed with either of said cam tracks, and trappers for yarn, said idle cam track being constructed to impart movement to the needles controlled thereby once in each revolution in order to clear said trappers. 100 105 110

4. In a rib-knitting machine of the cylinder type having upper and lower needle beds, the combination with a bank of web-holders adapted to cooperate with the needles of one of said beds to form a welt, of a cam track for actuating the needles in the other of said beds during the rib-knitting operation, an idle cam track for controlling the position of the needles in the last named bed during the formation of a welt, said cam tracks having portions common to both, needle sliders operable in said cam tracks, and an element associated with the common portions of said tracks and arranged for movement to a position for blocking the idle cam track when the needles are reciprocated in one direction and to a position clear 115 120 125 130

of said cam track when the needles are rotated, said needle sliders engaging said element to move the latter to one of the two positions.

5. In a rib-knitting machine of the cylinder type having upper and lower needle beds, the combination with a bank of web holders adapted to cooperate with the needles of one of said beds to form a welt, of
10 a cam track for actuating the needles in the other of said beds during the rib-knitting operation, an idle cam track for controlling the position of the needles in the last named bed during the formation of a
15 welt, said cam tracks having portions common to both, needle sliders operable in said cam tracks, an element associated with the common portions of said tracks and arranged for movement to a position for blocking
20 the idle cam track when the needles are reciprocated in one direction and to a position clear of said cam track when the needles are rotated, said needle sliders engaging said element to move the latter to one of
25 the two positions, and yieldable means for moving said element to the other of the two positions.

6. In a rib-knitting machine of the cylinder type having upper and lower needle beds, the combination with a bank of web holders adapted to cooperate with the needles of the upper bed to form a welt, of
30 means driven from the machine for shifting said bank of web holders axially of the cylinders to provide clearance between the upper and lower needle beds in the knitting of heel and toe pouches.

7. In a rib-knitting machine of the cylinder type having upper and lower needle beds, the combination with a bank of web holders adapted to cooperate with the needles of the upper bed to form a welt, of a cam for actuating said web holders, and means driven from the machine for shifting
45 said cam and web holders upwardly and axially of the cylinders to provide clearance between the upper and lower needle beds in the knitting of heel and toe pouches.

8. In a rib-knitting machine of the cylinder type having upper and lower needle beds, the combination with a bank of web holders adapted to cooperate with the needles of one of said beds to form a welt, of a cam track for actuating the needles in
50 the other of said beds during the rib-knitting operation, an idle cam track for controlling the position of the needles in the last named bed during the formation of a welt, needle sliders for the needles in said
55 last named bed, said sliders being arranged in two groups having long and short butts respectively for operative engagement with said cam tracks, a device movable into the path of movement of said butts for deflecting
60 the latter from one to the other of said
65

tracks, and means for moving said device in timed relation with the machine into the path traversed by the long butts during movement of the short butts past the device, and thereafter into the path traversed by the short butts during the movement of the long butts past the device.

In testimony whereof we have signed our names to this specification.
